Primary Examiner — Messina L Smith*Assistant Examiner* — Kwabena A. Ankobiah(74) *Attorney, Agent, or Firm* — Young Basile Hanlon & Macfarlane, P.C.(57) **CLAIM**

The ornamental design for a watch, as shown and described.

DESCRIPTION

FIG. 1 is a bottom, front, right perspective view of a watch, showing my new design;

FIG. 2 is a top, rear, right perspective view thereof;

FIG. 3 is a top, front, left perspective view thereof;

FIG. 4 is a front view thereof;

FIG. 5 is a rear view thereof;

FIG. 6 is a right view thereof;

FIG. 7 is a left view thereof;

FIG. 8 is a top view thereof; and,

FIG. 9 is a bottom view thereof.

The ornamental design which is claimed is shown in solid lines in the drawings. The broken lines in the figures illustrate portions of the watch that form no part of the claimed design.

1 Claim, 7 Drawing Sheets(56)
